UTILITY SHELF AND TOWEL BAR COMBINATION

Edgar M. Litzaw, 415 Cherry, Brea, Calif.

Filed May 29, 1959, Ser. No. 56,123

Term of patent 14 years

(Cl. D4—3)

Fig. 1 is a perspective view of a utility shelf and towel bar combination embodying my new design; Fig. 2 is a bottom plan view thereof; Fig. 3 is a side elevational view thereof; and Fig. 4 is a cross-sectional view thereof taken on the line 4-4 of Fig. 1.

I claim:

The ornamental design for a utility shelf and towel bar combination, as shown.
